FLOW METER

Shale J. Niskin, 9400 SW. 63rd Court,
Miami, Fla. 33156

Filed Mar. 29, 1972, Ser. No. 239,404

Term of patent 14 years

Int. Cl. D10—04

U.S. Cl. D10—96

FIG. 1 is a top plan view of a flow meter showing my new design, the tow cables shown broken-away to illustrate indeterminate length;

FIG. 2 is a right side elevational view thereof, the tow cables shown broken-away to illustrate indeterminate length;

FIG. 3 is a front elevational view thereof, the upper portion of the tow cables having been omitted for convenience of illustration;

FIG. 4 is a rear elevational view thereof.

The bottom plan view is substantially a mirror image of FIG. 1, while the left side is substantially like that of FIG. 2 with the opening omitted.

I claim:

The ornamental design for a flow meter, substantially as shown and described.
